CHILD'S SAFETY SCISSORS

Wilber M. Stilwell and Gladys F. Stilwell,
Vermillion, S. Dak.

Application February 3, 1950, Serial No. 142,196

1 Claim. (Cl. 30—233)

1

Our invention relates to a scissors for children's use.

The principal object of our invention is to provide a scissors which is completely safe in that there are no sharpened edges with which the child can come in contact, and which includes further attendant features wherein certain portions of the scissors provide an efficient guard.

A further object of our invention is to provide a scissors wherein preferred forms, the guard is in the form of an enlarged plate which will cover the cutting blade during any position of said blade.

A further object of our invention is to provide a scissors having the above features which also is easily operated and simple of manufacture.

With these and other objects in view, our invention consists in the construction, arrangement, and combination of the various parts of our device, whereby the objects contemplated are attained, as hereinafter more fully set forth, pointed out in our claim, and illustrated in the accompanying drawings, in which:

Figure 1 is a side elevation of one type of the scissors,

Figure 2 is a modified form,

Figure 3 is a sectional view of Figure 2 taken along the lines 3—3 of Figure 2,

Figure 4 is a detail, and

Figure 5 is a further modification.

Our invention contemplates the provision of a simple scissors which can be used by children, such scissors having certain features wherein none of the cutting edges of the scissors can contact the child in any way, and the scissors further being adaptable so that there are provided guard plates of sufficient size so that these plates can be ornamented with suitable attractive designs and the like.

Figure 1 illustrates one of the preferred forms of the invention in which the character 10 designates a plate, said plate being made of any suitable material such as plastic, metal or any other material, the plate having the upper arcuate boundaries 11, the plate further being attached to one of the finger portions 12 formed integrally therewith.

Pivoted by means of a suitable pin 13 to the flat plate 10 is the cutting element 14 having the lower edge 15, the member 14 terminating in the further finger grip portion 16.

The member 10 also includes the lower portion 17 having the curved edge 18, and formed within the portions 10 and 17 is a lengthened slot 19 which is preferably slightly larger at its outer

end 20 for the ready insertion of the material to be cut.

The portions 10 and 17 terminate in the blunt rounded portions 21, and formed integrally with the portion 11 is a thickened portion 22, such thickened portion being adapted to snugly engage the cutting portion 14 to thereby provide an efficient cutting engagement at all times.

It will be noted that the outer edge 23 of the member 14 will always be within the radius of the curved portion 11. The reason for this structure is that when the child is cutting the material, this edge will always be within the boundaries of the plate 10 as will be the edge 15, thereby insuring that the child will not be cut by the edge or any other portion of the scissors. The material, which is indicated by the dotted lines character 24, is fed into the slot 19 as shown, and thence with the usual shearing action imparted by the finger portions 12 and 16, the material is cut without injury to the child.

Figure 3 illustrates a modified form wherein a pair of outer plates 25 of identical conformation are employed, having the finger portions 26 with a spacer at 27, further spacers being indicated by the characters 28 and 29, the plates 25 having the lengthened slots 30.

In this structure a cutting blade 31 is interposed between the plates 25 and is pivotally engaged on the pin 32, the pin 32 having the reduced portions at 33, the larger portion 32 of which permits the scissors to engage one side of the plate without interference with the other side, the scissors being of slightly lesser width than the distance between the plates. The cutting member 31 includes the finger portion 34. This arrangement provides a double guard on either side and provides similar functions to that described in Figure 1.

Figure 5 illustrates a further form wherein the flat member 35 includes a raised edge 36 which limits the movement of the pivoted blade 37 as is clearly shown to thereby also provide a guard feature, the blade 37 being pivoted at 38, and having the edge 39 and blunt portions 40 and also having the finger portion 41, the plate 35 having the finger portion 42. The material receiving slot is indicated by the character 43. It will be noted that this latter structure also includes guard features as well. In this latter structure the members 42 and 41 can abut as can the finger portions in the other figures to limit downward movement of the cutting blade.

It will now be seen that we have provided the various advantages set forth in the objects of

our invention with various other advantages being readily apparent.

Some changes may be made in the construction and arrangement of the parts of our invention without departing from the real spirit and purpose of our invention, and it is our intention to cover by our claim any modified forms of structure or use of mechanical equivalents which may be reasonably included within its scope.

We claim as our invention:

A child's safety scissors comprising a plate member having a lengthened slot therein, a cutting blade member pivotally attached to said plate member adapted to pivot past said slot to provide means for cutting of material received in said slot, said plate member being of sufficient area so that the boundaries of said cutting blade are always within the outer edge of said

plate member to prevent accidental contact of said cutting portions with an operator of said scissors, said cutting blade and plate member having finger grip portions, said plate member having a thickened portion adjacent to the cutting edge of said blade to provide constant cutting edges.

WILBER M. STILWELL.
